BOTTLE CAPPING MECHANISM

Ransom J. Daniels, Whitestone, N. Y., assignor to
American Seal-Kap Corporation, Long Island
City, N. Y., a corporation of Delaware

Application July 29, 1933, Serial No. 682,812

11 Claims. (Cl. 226—92)

This invention relates to mechanism for applying caps to bottles and more particularly, though in its broader aspects not limited thereto, to the application to milk bottles of caps of the general type shown in the Baum patent, No. 1,169,283, March 1, 1927, for Bottle caps. This invention may be embodied in capping mechanism of the hand operated type, or in a power operated mechanism such as is used in conjunction with bottle filling machines.

One of the objects of this invention is to provide a better and more positive control of the caps as they are taken successively from a stack and applied in sealing relation to the bottles.

Further advantages will appear from a more complete description of an embodiment of the invention shown in the accompanying drawings in which—

Figures 1 and 2 are views partly in side elevation and partly broken away and in section showing a milk bottle capper of the hand operated type and showing a cap feeding mechanism in retracted and advanced positions, respectively.

Figure 3 is a perspective of the cap feed plate.

Figures 4 and 5 are fragmentary views partly in section and showing successive stages in the bottle capping operation.

Figure 6 is a transverse central section through the capping plunger head on line 6—6 of Figure 4.

Figure 7 is a section to a larger scale on line 7—7 of Figure 1.

Figure 8 is a section on line 8—8 of Figure 5.

Figure 9 is a perspective of the capping plunger head.

Referring to the drawings, at 1 is indicated a tubular member within which the neck of a bottle 2 to be capped may be inserted. This tubular member, as shown, is provided with an inclined face portion 3 at its lower end for engagement with the bottle. This tubular member is provided near its upper end with a pair of recesses or openings 4 extending therethrough in oppositely disposed positions, at the upper ends of which on each side are positioned pairs of outwardly extending ears 5, shown best in Figure 7. These ears are provided with openings 6 within which are mounted plugs 7 which may turn therein. Each of these plugs is shown as provided with a screw-driver slot at its outer end 50 and at its inner end with a perforation within which extends an end of a pivot shaft 8. Each shaft extends through the shank portion 9 of a cap supporting platform 10, each platform being thus pivotally mounted on the axis of a shaft 8 55 so that it may take a position extending trans-

versely of the axis of the bore of the member 1, as shown in Figures 1 and 2, or be moved downwardly into a recess 4, as shown in Figures 4 and 5. These platforms are normally held in their upper cap-supporting positions, for this purpose a pair of torsion springs 12 being shown. The intermediate portion of each of these springs 12 passes through a perforation 13 in one of the shank portions 9, is coiled around the shaft 12 and its ends are inserted in perforations 14 in 10 oppositely disposed plugs 6. By turning each plug 7 with the aid of a screw-driver engaging in its slot, each end portion of the torsion spring may be tensioned to the proper degree and then the plug may be fixed in adjusted angular position by tightening a set screw 15 thereagainst. Above the tubular member 1 is a tubular support 20 which is secured to the member 1 as by screws passing through openings 21 of mating flange portions on the members 1 and 20. Within the member 20 is reciprocably mounted a cap applying plunger 25. As shown this plunger is provided with a head 26 which presents the cap to the bottle and a tubular actuating portion 27 secured to this head.

The member 20 is provided with an upwardly extending sleeve portion 30 coaxial therewith and through which the tubular member 27 of the plunger passes. The upper end of this portion 30 is closed off as by a cap 31 through a central opening of which the member 27 passes and within this portion 30 is positioned a coil spring 32. This spring bears at its upper end against the lower face of the plug 31 and at its lower end against a washer 35 which is normally held 35 against the base of the portion 30 by this spring. The portion 27 is provided with a slot 36 within which rides a cross pin 37, the ends of which are supported in the slotted extremities of a pair of arms 38 of bell crank levers 39. These bell crank 40 levers are pivoted at opposite ends of a boss 40 shown as integral with the portion 30 and through which passes a pivot shaft 41. The opposite arms 42 of these bell crank levers are pivoted as at 43 to a pair of links 44, which, in turn, 45 are pivotally secured at their outer ends to a cap feed slide 45. This feed slide is mounted for reciprocation in a lateral extension 50 of the member 20, which has adjacent to the portion 20 a socket 54 for the reception of the lower end of 50 a tubular casing 51 within which may be positioned a stack of caps as indicated at 52. The feed slide 45 is shown as provided with an arcuate forward end 55 which may engage with the lowest cap of the stack so that on reciprocation 55

of this slide the caps are moved successively from the bottom of this stack over onto the supporting platforms 10 and beneath the plunger head 26, as shown in dotted lines in Figure 1 and in 5 full lines in Figure 2.

When the capping plunger is raised, as by moving the tubular member 27 upwardly, above the position shown in Figure 1, the cross pin 37 is engaged by the lower end of the slot 36 and is 10 moved upwardly with the member 27, thus moving the feed slide from its retracted position shown in Figure 1 to its advanced position shown in Figure 2, which feeds a cap 53 into position on the platforms 10 and beneath the plunger head 15 26. As shown, the raising of this member 27 is accomplished by pulling upwardly on the handle 60 shown as secured to its upper end, though it should be understood that this member may be raised by power when the mechanism is applied 20 to a power operated filling and capping machine. The weight of the parts may be sufficient to cause this feed action when the entire mechanism is lifted by the handle 60, or a handle 61 (see Figures 4 and 8) secured to any suitable 25 portion of the mechanism support may be grasped by one hand to hold the support while the handle 60 is grasped by the other and pulled upwardly. This upward motion of the member 27 acts to tension the spring 32, the cross pin 37 engaging the lower face of the washer 35 and moving it upwardly, as shown in Figure 3. The tubular member 1 may then be applied to the neck of a bottle and the handle 60 allowed to descend, whereupon the spring 32 pulls downwardly on the member 27 and retracts the feed slide 45, the plunger head 26 being then lowered into proximity with the cap 53. On pressing the handle 60 allowed to descend against the cap, further downward motion 40 of the plunger being a lost motion with respect to actuation of the feed slide, the cross pin 37 riding in the slot 36. The actuation of the feed device, both in feeding and retracting, takes place during the motion of the capping plunger within the upper portion of its stroke when it is remote 45 from cap-applying position, and out of the way of the cap, and the retraction is accomplished regardless of the final extent of downward capping motion of the plunger.

When the cap mechanism is intended to apply caps of the general construction shown in the Baum patent, to which reference has heretofore been made, the head 27 is provided in its lower face with an annular recess 65 within which the pouring lip housing 66 (see Figure 4) of the cap 50 may extend, this pouring lip housing being an annular generally U-shaped marginal portion of the cap which in capping position fits over the pouring lip 67 at the top of the bottle, as shown best 55 in Figure 5, the central portion of the cap extending down into the mouth of the bottle and into contact with the usual annular ledge 68 therein.

As shown best in Figure 6, this capping head 65 is provided with means for grasping the cap so as to control its movement to setting position on the bottle. Referring to this figure and Figure 9, it will be seen that the head is provided with oppositely disposed marginal openings or recesses 70 70 within which are positioned cap-grasping fingers 71. They are shown as yieldingly pressed toward each other at their lower ends by means of a spring 72 which extends across the head through openings 73 and has its ends engaged 75 in perforations 74 and 75 in these fingers. The

upper ends of these fingers are rockingly held to the head as by means of a pin 76 carried by each and engaging in an opening 77 in an upwardly extending flange portion 78 of the capping head.

In order to retract the supporting platforms 10 into their recesses so that the caps may be passed therebetween and into sealing engagement with the bottles, each of these platforms is shown as provided with upstanding lugs 80 which are engaged by downwardly extending rim portions 81 10 on the capping head when the plunger is depressed toward capping position. Thus as the plunger descends from the position shown in Figure 2, through the position shown in Figure 4, and to the full cap-applying position shown in Figure 5, the cap to be applied is grasped by the fingers 71 of the plunger and the supporting platforms 10 are retracted so that the plunger with a cap carried thereby passes between them and down into the capping position. Extension wings 20 25 85 projecting upwardly from the marginal portions of the capping head engage the faces of the platforms 10 and hold them in their retracted position, as shown in Figure 5, while the plunger is depressed, acting to cause them to be retained 30 retracted as long as the lower or cap applying face of the head is below the level of the upper faces of these platforms. When the plunger is raised they are permitted to spring upwardly into cap-supporting position only after the plunger has been retracted thereabove.

From the foregoing description of an embodiment of this invention it should be evident to those skilled in the art that various changes and modifications might be made without departing 35 from the spirit or scope of this invention as defined by the appended claims.

I claim:

1. In a bottle capping mechanism, a cap-applying plunger having a cap-engaging face provided with an annular recess to receive a pouring lip housing portion of a bottle cap, said plunger having side recesses, and fingers positioned in said recesses and engageable with side wall portions of said pouring lip housing to retain a cap 40 on said plunger.

2. In a bottle capping mechanism, a cap-applying plunger having a cap-engaging face provided with an annular recess to receive a pouring lip housing portion of a bottle cap, said plunger having oppositely disposed side recesses, fingers positioned in said recesses and engageable with side wall portions of said pouring lip housing, and a spring joining said fingers for holding said fingers in yielding engagement with said cap. 50

3. In a bottle capping mechanism, a cap-applying plunger having a cap-engaging face provided with an annular recess to receive a pouring lip housing portion of a bottle cap, said plunger having oppositely disposed side recesses, 60 fingers positioned in said recesses and engageable with side wall portions of said pouring lip housing, said plunger having an aperture extending between said side recesses, and a coil spring extending through said aperture and joining said fingers for holding said fingers in yielding engagement with said cap.

4. A bottle capping mechanism, comprising a tubular member within which the mouth of a bottle to be capped may be presented, downwardly yieldable means on which a cap may be supported within said member above said bottle mouth, and a plunger movable relative to the bottle for forcing said cap axially of said tubular member past said supporting means and seating 75

- it on said bottle, said plunger having a portion engageable with said yielding means and moving it out of cap-supporting position during the capping motion.
5. A bottle capping mechanism, comprising a tubular member within which the mouth of a bottle to be capped may be presented, downwardly yieldable means on which a cap may be supported within said member above said bottle mouth, a plunger movable relative to the bottle for forcing said cap axially of said tubular member past said yielding means and seating it on said bottle, and means carried by said plunger for grasping said cap.
10. A bottle capping mechanism comprising a tubular member within which the top of a bottle to be capped may be presented, a platform normally extending transverse to the axis of said tubular member spaced from said bottle top and yieldable theretoward, and upon which a cap to be applied may be supported, a cap-applying plunger movable axially within said tubular member, means acting to move said plunger to press the cap supported on said platform toward said bottle past said platform and to apply said cap to said bottle, and means on said plunger for holding said platform in yielded position while said plunger is in cap-pressing position.
15. A bottle capping mechanism comprising a tubular member engageable with a bottle, a cap-applying plunger reciprocable in said member from and to capping position, a platform normally extending transverse to the axis of said member for supporting a cap beneath said plunger preparatory to a capping movement thereof, said member having a pair of spaced ears extending therefrom, and a slot between said ears into which said platform may be retracted from the path of said plunger, said platform having a shank portion extended between said ears, a pair of oppositely disposed plugs seated in openings in said ears, a pivot shaft carried by said plugs and forming a pivotal axis for said shank portion, a torsion spring surrounding said shaft and engaging said shank portion and having its ends inserted in openings in said plugs, and means for securing said plugs against rotation in said ears.
20. A bottle capping mechanism, comprising a tube within which the mouth of a bottle to be capped may be presented, a pair of platforms each pivoted transverse to the axis of said tube and outwardly of the bore thereof, means yieldingly holding said platforms extended toward each other transverse to said axis so as together to form a support on which a cap to be applied to said bottle may rest, a capping plunger movable axially within said tube in position to force said cap downwardly and tilt said platforms to permit said cap to pass therebetween and to seat said cap on said bottle mouth, and means on said plunger for holding said platform in yielded position while said plunger is in cap pressing position.
25. A bottle capping mechanism, comprising a tube within which the mouth of a bottle to be capped may be presented, a pair of platforms each pivoted transverse to the axis of said tube and outwardly of the bore thereof, means yieldingly holding said platforms extended toward each other transverse to said axis so as together to form a support on which a cap to be applied to said bottle may rest, and a capping plunger movable axially within said tube in position to force said cap downwardly and tilt said platforms to permit said cap to pass therebetween and to seat said cap on said bottle mouth, said plunger having portions engageable with said platforms and holding said platforms downwardly tilted whenever the lower face of said plunger is below the level of their cap-supporting faces.
30. A bottle capping mechanism comprising a tube for engagement with the neck of a bottle below its mouth, said mouth extending into said tube a cap-applying plunger having a cap-engaging portion and reciprocable in said tube, means for supporting a stack of caps, means operatively connected to said plunger for positively feeding a cap from said stack beneath said plunger by upward motion of said plunger from a position intermediate the ends of the stroke thereof, means for holding said cap beneath said plunger, means yieldingly connecting said feeding means and plunger for retracting said feeding means on descent of said plunger to said intermediate position above said cap, and a yieldable mounting for said holding means to permit downward movement of said plunger from said intermediate position to present and apply said cap to said bottle.
35. In a capping mechanism, a tube for engagement with the neck of a bottle below its mouth, said mouth extending into said tube a cap-applying plunger having a cap-engaging portion and reciprocable in said tube, means for supporting a stack of caps, means operatively connected to said plunger for positively feeding a cap from said stack beneath said plunger by upward motion of said plunger from a position intermediate the ends of the stroke thereof, means for holding said cap beneath said plunger, means yieldingly connecting said feeding means and plunger for retracting said feeding means on descent of said plunger to said intermediate position above said cap, and a yieldable mounting for said holding means to permit downward movement of said plunger from said intermediate position to present and apply said cap to said bottle.
40. A bottle capping mechanism comprising a member engageable with a bottle adjacent to its top, a cap-applying plunger reciprocably carried by said member, means carried by said member for holding a stack of caps, a device for feeding caps successively from said stack into cooperative relation to said plunger, a spring connection to said plunger for retracting said device from cap-feeding position, and connections between said plunger and cap feeding device for actuating said device to feed a cap on reciprocation of said plunger beyond an intermediate position and including lost motion from said intermediate position to capping position of said plunger without effect on said device.
45. A bottle capping mechanism comprising a member engageable with a bottle adjacent to its top, a cap-applying plunger reciprocably carried by said member, means carried by said member for holding a stack of caps, a device for feeding caps successively from said stack into cooperative relation to said plunger, a spring connection to said plunger for retracting said device from cap-feeding position, and connections between said plunger and cap feeding device for actuating said device to feed a cap on reciprocation of said plunger beyond an intermediate position and including lost motion from said intermediate position to capping position of said plunger without effect on said device.
50. A bottle capping mechanism comprising a member engageable with a bottle adjacent to its top, a cap-applying plunger reciprocably carried by said member for holding a stack of caps, a device for feeding caps successively from said stack into cooperative relation to said plunger, a spring connection to said plunger for retracting said device from cap-feeding position, and connections between said plunger and cap feeding device for actuating said device to feed a cap on reciprocation of said plunger beyond an intermediate position and including lost motion from said intermediate position to capping position of said plunger without effect on said device.
55. A bottle capping mechanism comprising a member engageable with a bottle adjacent to its top, a cap-applying plunger reciprocably carried by said member for holding a stack of caps, a device for feeding caps successively from said stack into cooperative relation to said plunger, a spring connection to said plunger for retracting said device from cap-feeding position, and connections between said plunger and cap feeding device for actuating said device to feed a cap on reciprocation of said plunger beyond an intermediate position and including lost motion from said intermediate position to capping position of said plunger without effect on said device.

RANSOM J. DANIELS.
